UNITED STATES PATENT OFFICE.

PAUL TIMBERLAKE WOLFE AND WILLIAM HENRY BOVARD, OF LOS ANGELES,
CALIFORNIA.

AEROPLANE.

1,353,692.

Specification of Letters Patent. Patented Sept. 21, 1920.

Application filed November 25, 1919. Serial No. 340,456.

To all whom it may concern:

Be it known that we, PAUL T. WOLFE and WILLIAM H. BOVARD, citizens of the United States, and residents of Los Angeles, in the 5 county of Los Angeles and State of California, have invented a new and Improved Aeroplane, of which the following is a full, clear, and exact description.

This invention relates to improvements in 10 aeroplanes, an object of the invention being to provide an improved arrangement of rotary planes which serve to support the device in the air and to elevate the same or permit the descent thereof.

15 A further object is to provide an aeroplane which will quickly ascend in a substantially vertical line and which can be operated to start and light without the necessity of running over the ground.

20 A further object is to provide an improved construction and arrangement of rotary planes which are caused to move in opposite directions and are located substantially at a horizontal.

25 A further object is to provide a plurality of pairs of planes with improved means for imparting rotary motion to the pairs of planes to turn them in opposite directions.

30 A further object is to provide improved means for elevating and propelling an aeroplane.

With these and other objects in view the invention consists in certain novel features of construction, and combinations and arrangements of parts, as will be more fully hereinafter described and pointed out in the claims.

In the accompanying drawings—

Figure 1 is a view mainly in side elevation 40 but partly in section illustrating our invention; and

Fig. 2 is an enlarged view in longitudinal section through the driving mechanism.

1 represents a vertical post supporting a 45 pair of tubular telescoping shafts 2 and 3 thereon, the shaft 2 being appreciably longer than the shaft 3 and extending above the same. A basket or car 4 is secured by stays 5 to a collar 6 mounted loosely on the shaft 50 3 and having ball bearings 6' located between the same and a fixed collar 7 on the shaft 3.

The post 1 is secured at its lower end to a motor base 8 and above its lower end is made 55 in the form of a ring 9 receiving a motor

10. Suitable frames 11 and 12 are supported in the basket or car 4 and in the upper portions of these frames 11 and 12, shafts 13 and 14 respectively are mounted. The shafts 13 and 14 are normally horizontal and in 60 alinement and the shaft 14 carries an ordinary propeller 15 to move the aeroplane horizontally.

The shafts 13 and 14 are provided with beveled pinions 16 and 17 respectively which 65 mesh with beveled gears 18 and 19 secured to shafts 2 and 3 respectively. A motor shaft 20 is provided with a sprocket wheel 21 connected by a sprocket chain 22 with a sprocket wheel 23 on shaft 13 so that motion 70 is transmitted from the shaft 13 through the pinion 16 to drive the gear wheels 18 and 19 in opposite directions and transmit motion to the pinion 17 and shaft 14 to turn the propeller 15.

75 The shafts 2 and 3 at their upper ends are provided with brackets 24 supporting horizontal arms 25 projecting in opposite directions. The arms 25 are normally horizontal and the arms 25 of the shaft 3 are located 80 appreciably lower than the arms 25 of the shaft 2. These arms 25 support planes 26 which are concave on one side and convex on the other side and are made up of suitable framework and covering to render them 85 sufficiently strong and as light as possible to perform their functions. The planes are further strengthened by longitudinal trusses 27 above the arms 25 and by diagonal braces 28 below the arms 25. These braces 28 are 90 connected to collars 29 secured to the shafts 2 and 3 respectively and provided with ball bearings 30 to reduce friction to a minimum.

As indicated in Fig. 1, we preferably employ two or more pairs of planes projecting 95 laterally in opposite directions, one pair located above the other. The planes of each pair are reversely positioned so that when the shafts are turned, the concave faces of the planes are always the advanced faces so 100 that the rotary motion imparted to the planes has a tendency to elevate.

The operation is as follows: As above explained, the shaft 13, through the medium of the pinion 16, turns the gear wheels 18 105 and 19 in opposite directions. As these gear wheels are fixed to the shafts 2 and 3 respectively, the planes 26 are caused to move in a circular, normally horizontal path and the lower planes are moved in a direction op- 110

posite to the movement imparted to the upper pair of planes. This movement of the planes insures an elevation of the aeroplane in a substantially vertical line and the speed 5 of such elevation is in accordance with the rotary speed of the planes. It is therefore apparent that by decreasing the speed of the planes, the device may maintain any desired elevation in the air or may be allowed to 10 quickly descend, and while we illustrate a propeller 15 which is connected directly by the shaft 14 and pinion 17 to the gears 18 and 19, it is obvious that various other expedients may be resorted to to exactly control the movement of the aeroplane in the 15 direction of flight.

Various slight changes may be made in the general form and arrangement of parts described without departing from the invention, and hence we do not limit ourselves 20 to the precise details set forth but consider ourselves at liberty to make such changes and alterations as fairly fall within the spirit and scope of the appended claims.

25 We claim:

1. An airship, comprising a car, a vertical post projecting upwardly from the car, tubular shafts on the posts, rotary planes projecting laterally from the vertical tubular 30 shafts, frames on the car projecting upwardly from the car, alined shafts in said frames, means for transmitting motion from

one of the horizontal shafts to the tubular shafts to turn the latter in opposite directions, means for transmitting motion from 35 the tubular shafts to the other horizontal shafts, a propeller on one of said horizontal shafts, and means for transmitting motion to one of said horizontal shafts.

2. An airship, comprising a car, a vertical 40 post projecting upwardly from the car, tubular shafts on the posts, rotary planes projecting laterally from the vertical tubular shafts, frames on the car projecting upwardly from the car, alined shafts in said 45 frames, a pair of beveled gear wheels on the tubular shafts, horizontal shafts supported in the frames, pinions on the horizontal shafts meshing with the beveled gears, a propeller 50 on one of said horizontal shafts, a motor supported in the car, and means for transmitting motion from the motor to one of said horizontal shafts.

3. An airship, comprising a car, a vertical post projecting upwardly from the car 55 and having a ring portion at its lower end, a motor mounted in the ring portion, horizontal rotary planes mounted on the post, means for turning the planes, and means for transmitting motion from the motor to the 60 planes.

PAUL TIMBERLAKE WOLFE.
WILLIAM HENRY BOVARD.
